CHROMATIC DEVICE

Frank R. Higley, Cleveland Heights, Ohio

Application November 18, 1937, Serial No. 175,280

14 Claims. (Cl. 46—49)

This invention relates to toys of the chromatic whirligig variety which include a pair or more of colored disks disposed in overlapping relation with each other upon parallel axes and mounted for rotation in unison about an intermediate parallel axis and each for individual rotation about its own axis. Operation of such a toy involves its rotation with periodic reversal of direction obtainable by means such as disclosed in the three patents to Van Altena, 194,628 of August 28, 1877, 208,351 of September 24, 1878, and 1,041,380 of October 15, 1912.

The general objects of the invention are to provide an article of such class having the minimum number of parts, each of the simplest possible form so that the article is producable to the user at a very minimum of cost of materials, shipment and assembly; and furthermore to provide that the chromatic effects produced be of greater brilliance during operation of the device and the appearances of parts more attractive when stationary than has heretofore been produced in the art.

The invention particularly contemplates employment of but a single pair of colored disks arranged in overlapping relation, and operable by means passing through the disk centers, such as a twisting cord or cords. And more particularly objects of the invention are to so arrange the colors on the disks that no more than two primary colors will appear to the observer during operation, whereby the visible pattern will be ever changing yet will always contain only concordant colors and these of brilliant intensity and symmetrically disposed in relatively sharply defined areas.

Another object of the invention, contributing to this end, is to interconnect the disks by means largely concealed and disposed generally between their overlapping portions. A further object is to so color the disks as to produce the described effect when the device is in operation yet display not only the primary colors but the secondary colors compounded therefrom when the parts are stationary.

Also contributory to these ends and as an important feature of the invention, the latter includes gearing means for maintaining an indexed relation between the disks while permitting their adjustment upon their own axes for color changing purposes.

Still another object is to provide improved spinning stability of the device.

The exact nature of this invention together with further objects and advantages thereof will

be apparent from the following description taken in connection with the accompanying drawings, in which Figs. 1, 2 and 3 are face views of an embodiment of the invention showing the parts in various adjusted positions; Fig. 4 is a typical section through the same as in the plane of line 4—4, Fig. 2; Fig. 5 is a face view of another embodiment of the invention; Fig. 6 is a typical section as in the plane of line 6—6, Fig. 5; Fig. 7 is a perspective view illustrating a belt employable in the embodiment of Figs. 5 and 6; Fig. 8 is a sectional detail illustrating the manner of employment of such belt; Figs. 9 to 12 show another modification, Figs. 9 and 10 being face and edge views of the same, Fig. 11 being a view of the yoke member and Fig. 12 a perspective view of one of the pinion members employed in this modification.

With reference now to the drawings and first to the form of the invention illustrated in Figs. 1 to 4 thereof, I generally represent each of a pair of similar disks which may be of sheet metal, cardboard or the like, having a central small circular opening finished by a metal eyelet 2 or the like. Each disk also has a pair of diametrically opposed openings 3.

The disks are disposed in partially overlapping relation each with a peripheral part adjacent the center of the other.

The disks are maintained in such overlapping relation by a pair of links 4, each link being disposed between the disks and interconnecting them at one of the openings 3 of each disk, so that the assembly has the characteristics of a four-bar linkage. As illustrated, at each joint the end of the link is bent to extend through the opening 3 of the disk, the overhanging extremity of the link wire being flattened as illustrated to maintain the assembly. It will be apparent that the disks may be mounted for alternate rotation together as a unit, in opposite directions about a unit axis medial of their individual axes by means located in their central openings. Such means are here indicated as sections of an endless cord 5 threaded through the eyelets 2 with stretches between the operator's hands. It will also be apparent that the links 4 permit adjustment of the disks about their individual axes while serving to gear them together for maintaining an indexed relation between them as well as fixing the spacing between their centers and generally interconnecting the disks.

The proportioning and arrangement of the parts, and particularly the form of the links and the location of the openings 3, are preferably

such that each disk may have maximum adjustment about its axis. One limit of such adjustment is indicated by the parts positioned as in Fig. 1 wherein the two links engage each other between the disks as illustrated in dotted lines approximately as the arched part of each link engages the cord 5 adjacent the disk center. Adjacent ends of the links may pass each other during such adjustment, as illustrated in Figs. 2 and 10 4, and the total adjustment possible for each disk in the form illustrated is 30°.

Both disks are colored as indicated, each bearing three equal segmental areas, each area having one of the three primary colors, yellow, red 15 and blue. The colors are so located on the disks and the latter so oriented that each color area of each disk is in symmetrically opposed relation with the corresponding area of the other disk.

In operation, with each reversal of the disks 20 relative to their common axis of whirl, each will be caused by its inertia together with the inertia of the links 4, to have motion about its individual axis, such inertia always acting in the same direction as to both disks, that is, tending to move 25 both simultaneously either clockwise or counter-clockwise, and the entire assembly is unstable as to such disk adjustment.

As to colors it will be evident that the arrangement described will always produce, when 30 the device is whirling, a pattern having a central portion of one clearly defined color and a peripheral portion of another clearly defined color, one of these portions being a primary color and the other a secondary color. The links 4 being 35 always largely concealed between the overlapping portions of the disk, the central portion of the whirling unit will have maximum brilliance, and the outer portions will likewise have the greatest possible intensity since opposed extremities of the disks are always similarly colored.

To prevent jamming of the disks 1 upon the links 4, each disk may be slightly bent outwardly from the other as at 6.

With reference now to the modification of Figs. 45 5 and 6, the disks are similar to each other and similarly disposed as in the modification of Figs. 1 to 4. Each is rotatably mounted upon one end of a link 10 here shown as of strap form, which link is disposed generally between the overlapping portions of the disks. Eyelets 11 are employed for mounting the disks upon the link so that in operating the device the stretches of the cord 12 are threaded through these eyelets for spinning the device, as shown in Fig. 6.

55 The faces of the disks are colored as indicated in Fig. 5 principally with the three primary colors red, yellow and blue, generally as before. But as where transparent colors are employed they may be applied to provide overlapping segmental areas wherein the corresponding secondary colors are produced so that the general pattern is one of a trilobate of three different secondary colors upon a background of three primary colors, each secondary color lying between the two primary colors of which it is compounded. The resultant effect is that the device is more attractive when stationary.

To maintain the disks in their oriented relation, a resilient belt as of rubber may be provided 70 of sectional form as indicated in Fig. 7, and trained about the peripheries of the disks as indicated in Fig. 8, with stretches between the disks. Then, the disks once properly oriented as in Fig. 5, such orientation will be maintained 75 although the disks may freely rotate upon their

own centers. If the lobate pattern of Fig. 5 be employed, the resultant appearances when the disks are rotating either about their own centers or about the common center, will be identical with the arrangement of the modification of 5 Figs. 1 to 4. It may be noted that the link 10 being disposed substantially entirely between the overlapping portions of the disks, is substantially invisible so that the color intensity of the whirling pair is substantially unimpaired. 10

With reference now to the modification of Figs. 9 to 12, the disks 20 are colored as illustrated like those of Figs. 1 to 4, or they may be colored as illustrated Fig. 5. They are mounted each for rotation about its own center upon a sheet 15 metal stamping of the form illustrated in Fig. 11, which comprises a yoke member 21 disposed between and interconnecting the disks as does the link member 10 of the modification of Figs. 5 and 6. The yoke is provided with punched 20 holes 22 to receive metal eyelets 23 by which the disks are mounted generally as in the previous modification.

For maintaining the indexed relation between the disks while permitting their rotation in unison about their centers, they are peripherally toothed as illustrated Fig. 9, and pinion means 24 are mounted upon the yoke 21 in intermeshing relation with the disk teeth. For the purpose the yoke has a pair of opposed slotted extensions 30 25 between its holes 22 and projecting slightly beyond the disks as illustrated Fig. 9. A pair of pinions 24 are provided, each having a central annular groove as illustrated Fig. 12 and each thus comprising in effect a double pinion having 35 a short central spindle, the length of which is very slightly greater than the thickness of the yoke 21 and the diameter of which is slightly less than the width of the yoke slots.

In the assembly each double pinion is disposed 40 as indicated Figs. 9 and 10, its spindle bearing in the end of its yoke slot and its teeth intermeshing with those of both disks 20, the slots being of suitable length for the purpose.

The large central opening in the yoke 21 together with the weight of the two double pinions, provides improved balance of the assembly in operation. While for simplicity in each of the modifications disclosed, but two disks have been illustrated and specifically described, it will be 50 apparent that three or more disks could be interconnected in a single device, both for indexed adjustment about their individual centers and for rotation in unison about a common central axis following the arrangement of any of the 55 three modifications disclosed, with adjacent disks interconnected by means located between their overlapping portions.

Also it will be obvious that in each modification both faces of each disk may be colored so that 60 the complete device is two-faced; or, of course, advertising or like matter may be preferred for the reverse face.

What I claim is:

1. In an article of the class described, a pair 65 of similar disks disposed in partially overlapping relation and means extending between said disks and mounting them for adjustment about their axes.

2. In an article of the class described, a pair 70 of similar disks disposed in partially overlapping relation, means extending between said disks for mounting them for adjustment about their axes, and means gearing said disks to each other for equalizing their said adjustment. 75

3. In an article of the class described, a pair of similar disks disposed in partially overlapping relation and means extending between said disks and interconnecting them for adjustment about 5 their axes while maintaining their oriented relation.

4. In an article of the class described, a pair of similar disks disposed in partially overlapping relation, link means disposed between the overlapping portions of said disks, and means mounting said disks upon said link means for rotation about their axes.

5. An article of the class described, comprising a pair of similar disks disposed in partially overlapping relation with the central part of each adjacent the periphery of the other, means interconnecting said disks while permitting their adjustment about their axes, said means being disposed generally between the overlapping disk 20 portions to be substantially concealed thereby and there extending between the central parts of the disks, and means for supporting said disks for their rotation about a common axis intermediate the disk axes.

25 6. An article of the class described comprising a pair of similar disks, each having a central opening, said disks being disposed in partially overlapping relation with the opening of each adjacent the periphery of the other, means interconnecting said disks while permitting their adjustment about their axes, said means being disposed generally between the overlapping disk 30 portions and extending between said openings, and means for supporting said disks for their rotation about a common axis and comprising flexible members extending through said openings.

7. An article of the class described comprising a pair of similar disks disposed in partially overlapping relation with the central part of each adjacent the periphery of the other, means extending between said disks and mounting them for adjustment about their axes, and means gearing said disks to each other for equalizing their 15 said adjustment.

8. An article of the class described comprising a pair of similar disks disposed in partially overlapping relation with the central part of each adjacent the periphery of the other, means mounting said disks for adjustment about their axes, and belt means gearing said disks to each other for causing said adjustment to be equal and similar for both disks.

9. An article of the class described comprising a pair of similar disks disposed in partially overlapping relation with the central part of each adjacent the periphery of the other, means

mounting said disks for adjustment about their axes, and means gearing said disks to each other for causing said adjustment to be equal and similar for both disks, and comprising belt means trained over and stretching between the peripheries of said disks. 5

10. An article of the class described, comprising a pair of similar peripherally toothed disks disposed in partially overlapping relation, a yoke disposed between the disks, means mounting each 10 disk upon said yoke for rotation about its axis, and pinion means mounted on said yoke and intermeshing with the teeth of said disks to maintain their oriented relation while permitting their said rotation. 15

11. An article of the class described, comprising a pair of similar peripherally toothed disks disposed in partially overlapping relation with the central part of each adjacent the periphery of the other, a member disposed generally between the overlapping portions of the disks to be substantially concealed thereby, means mounting each disk upon said member for rotation about its axis, and pinion means mounted on said member and intermeshing with the teeth of said 20 disks to maintain their oriented relation while permitting their said rotation. 25

12. In an article of the class described, a pair of similar disks disposed in partially overlapping relation with the central part of each adjacent the periphery of the other, each disk having a central opening, and link means disposed between said disks and interconnecting them to permit their simultaneous adjustment about their respective centers while maintaining their indexed relation. 30 35

13. In an article of the class described, a pair of similar disks disposed in partially overlapping relation with the central part of each adjacent the periphery of the other, each disk having a central opening, and link means disposed between said disks and interconnecting them to permit their simultaneous adjustment about their respective centers while maintaining their indexed relation, said link means being of arched 40 45 form to increase the permissible adjustment while clearing said openings.

14. A disk for the purpose described having its face bearing three primary colors of transparent material, each in an area bounded inwardly by an arc having the radius of the disk intersecting the center of the disk, said areas somewhat overlapping to produce relatively slight areas, between those of adjacent primary colors, bearing the secondary color compounded therefrom. 50 55

FRANK R. HIGLEY.
